EX

OR D 644

No. 644.

John Abendroth.

Design for Cooking Stove or Summer Range.

Patented May 2, 1854

Des. 644

John Abendroth, of Port Chester, N.Y.
Letters Patent No. 644 - Dated May 2nd, 1854.

The schedule referred to in these Letters Patent, & making part of the same.

To all whom it may concern:

Be it known that I, John Abendroth, of Port Chester, in the County of West Chester, State of New York, have invented and produced a new and original design for ornamenting stoves and summer ranges; and I do hereby declare that the following is a full and exact description of the same, reference being had to the annexed drawing which is a perspective view of my improvement.

- A is a top plate.
- B end-plate.
- C side plate.
- D oven-door,
- E register,
- F bottom plate,
- G legs,
- H exit smoke pipe.

The interior of my range is constructed in any of the ordinary forms. The top-plate A is ornamented in the manner shown in the drawing, likewise the side plate C, the bottom plate F, the legs G, & the register E. These ornaments are cast in alto-relievo upon the exterior of the plates of the various parts referred to. The upper ornaments on the plate C, consist of an ornamental vine having a portrait in the center. The ornaments on the oven-door D, represent ornamental scrolls & vines having a portrait in the center surrounded by two small winged figures carrying a wreath. Upon the lower plate F, there is also ornamental scroll-work having a face in the center, and on the other parts there are ornamental designs in alto-relievo, as shown in the drawing.

End

6.1.4

Having thus described my improvement I claim:-

The combination of mouldings and ornaments as arranged on the summer range, the whole forming an ornamental design.
